CLAIM

The ornamental design for a telephone network interface apparatus, as shown and described.

DESCRIPTION

FIG. 1 is a front elevational view of a telephone network interface apparatus showing our new design in closed position;

FIG. 2 is a right side elevational view thereof;

FIG. 3 is a rear elevational view thereof;

FIG. 4 is a left side elevational view thereof;

FIG. 5 is a front, right and bottom perspective view

thereof, with the subscriber cover in fully opened position, and

FIGS. 6 and 7 are respectively bottom and top plan

views thereof.

FIG. 1

FIG. 2

FIG. 3

FIG. 4

FIG. 5

FIG. 6

FIG. 7
